UNITED STATES PATENT OFFICE

138,338

DESIGN FOR A BOAT OR THE LIKE

Carl H. Clement, Jr., United States Army,
Fort Belvoir, Va.

Application April 2, 1943, Serial No. 109,890

Term of patent 14 years

(Cl. D71—1)

To all whom it may concern:

Be it known that I, Carl H. Clement, Jr., of the Corps of Engineers, United States Army, a citizen of the United States, now stationed at Fort Belvoir, Virginia, have invented a new, original, and ornamental Design for Boats or the like, of which the following is a specification, reference being had to the accompanying drawings, forming part thereof.

Fig. 1 is a side perspective of a boat or the like, showing my new design;

Fig. 2 is a rear perspective view of same.

Figure 3 is a bottom perspective view of the boat; and Figure 4 is a top plan view thereof.

I claim:

The ornamental design for a boat or the like, as shown.

CARL H. CLEMENT, JR.
